UNITED STATES PATENT OFFICE.

FRANK LEMAN, OF ELGIN, ILLINOIS.

MACHINE FOR POINTING, DRILLING, AND REAMING.

SPECIFICATION forming part of Letters Patent No. 380,496, dated April 3, 1888.

Application filed August 5, 1886. Serial No. 210,096. (No model.)

To all whom it may concern:

Be it known that I, FRANK LEMAN, of Elgin, in the county of Kane, and in the State of Illinois, have invented certain new and useful Improvements in Mechanism for Pointing, Drilling, and Reaming; and I do hereby declare that the following is a full, clear, and exact description thereof, reference being had to the accompanying drawings, in which—

Figure 1 is a perspective view of my machine as arranged for use. Fig. 2 is a plan view of the upper side of the same. Fig. 3 is a like view of the upper end of the journaled head. Fig. 4 is a front elevation of said machine. Figs. 5 and 6 are elevations of opposite sides of the same. Fig. 7 is a vertical central section of said machine upon a line extending from front to rear. Fig. 8 is an enlarged section of the journaled head upon a line through its longitudinal axis. Fig. 9 is an enlarged vertical central section of one of the chucks, and Fig. 10 is a horizontal section of the same upon line xx of Figs. 8 and 9.

Letters of like name and kind refer to like parts in each of the figures.

The object of my invention is to enable the operations of pointing, drilling, and reaming to be simultaneously carried on upon a like number of parts; and to this end said invention consists, principally, in an organization in which is combined a series of rotatable work-holding chucks that are adapted to have a step-by-step rotation around a common center, a series of tool-spindles that are less in number than said chucks, and are each adapted to carry one of a series of pointing, drilling, and reaming or counterboring tools, means whereby each of said chucks may be moved into line with each of said tools and caused to rotate, and means whereby said tools may be simultaneously moved toward or from said chucks, whereby all of the various operations of pointing, drilling, and reaming or counterboring may be simultaneously carried on upon an equal number of pieces of work, substantially as and for the purpose hereinafter specified.

It consists, further, in an organization in which is combined a series of tools that are adapted by successive action to point, drill, and ream or counterbore, a series of rotatable work-holding chucks that exceed said tools in number and are each adapted to be moved by

successive steps into line with each of the latter, means whereby said tools may be simultaneously moved toward and from said chucks, 55 and means whereby each of said chucks, after having passed within the line of action of each tool of the series, has a period of rest, whereby each of the said operations of pointing, drilling, and reaming or counterboring 60 may be carried on simultaneously with the insertion of new and the removal of completed work, substantially as and for the purpose hereinafter shown.

It consists, further, in an organization in 65 which a series of chuck-spindles are journaled at equidistant points within a pivoted head that is adapted to have a step-by-step rotation around or upon its pivotal bearing, in combination with means, substantially as shown, 70 whereby as each spindle is moved with said head one step from a predetermined point it is caused to revolve within its bearings, and its revolutions are caused to cease when by the farther partial rotations of said head said 75 spindle again reaches its starting-point, substantially as and for the purpose hereinafter set forth.

It consists, further, in an organization in 80 which a series of chuck-holding spindles are journaled at equidistant points within a pivoted head that is adapted to have a step-by-step rotation around or upon its pivotal bearing, in combination with means, substantially as set forth, whereby as each spindle is moved 85 from a predetermined point by the partial rotation of said head its chuck is automatically closed and the spindle caused to revolve within its bearings, and when by the complete rotation of said head said spindle reaches its start- 90 ing-point it is automatically disconnected from its rotating mechanism and its chuck simultaneously opened, substantially as and for the purpose hereinafter shown and described.

In the carrying of my invention into practice I employ a vertical frame, A, which has the general form shown in Fig. 1, and at its lower end spreads out into a suitable base. To the front side, near the longitudinal center of said frame, is secured a housing, B, that has 95 a plain cylindrical interior, which from each end about one-fourth its length is made slightly conical.

Journaled within the housing B is a cylin-

drical head, C, which upon one end has formed a conical periphal enlargement, c, that corresponds to and fits within the contiguous conical face b, while upon the opposite lower end 5 of said head is fitted a section, B', that is adapted to conform to the conical face b at such point, the construction being such as is usually employed for preventing longitudinal motion of a part without interference with its 10 free rotation.

At equidistant points around the axis of the head C are journaled a number of spindles, D, each of which is adapted to rotate therein by means of a shaft, E, that is journaled vertically within the axis of said head and within 15 a bearing, F, which is secured to the base of the frame A. Secured to said shaft within the central portion of the head C is a gear-wheel, G, that meshes with a pinion, H, which is journaled upon each of said spindles, the arrangement being such that said pinions are constantly rotated whenever said shaft is in motion.

Upon each spindle D, above its pinion H, is 25 placed a clutch, I, which is locked in place thereon circumferentially, while free to move lengthwise of the same within certain limits. The lower end of said clutch is adapted to engage with the upper end of said pinion, and 30 is held in such engagement with a yielding pressure by means of a spring, i, that is placed between its upper end and a collar, d, which is secured upon said spindle. This construction causes the motion of said pinion to be communicated to said spindle whenever the former and said clutch are in engagement.

The clutch I is released from engagement with the pinion H by means of a rod, K, which extends from below the lower end of the spindle D upward within the same to the level of 40 said clutch, where it is connected with the latter by means of a bolt or pin, k, that passes horizontally through said parts and through two vertically-elongated slots, d', within said spindles. Each spindle D carries a chuck, L, which may be of any usual form to adapt it to the work to be done, but which in the machine under consideration is of the kind known as 45 "clamping-chucks," and is provided upon its flat enlarged upper end or head, l, with a clamp, l', that is held down upon the same by means of a bolt, l', which passes through a central slot in said clamp, and through a like opening, l'', in said head l, downward into an annular collar, M, that is placed around said chuck beneath said head.

At suitable points between the collar M and the head l are placed a number of spiral springs, m, preferably four, which exert a downward 50 pressure and operate to hold the clamp l' downward upon said head with sufficient force to cause any article that is placed beneath the inner end of said clamp to be firmly held in place.

In order that the clamp l' may be raised so 60 as to release an article held thereby, or to permit of the insertion beneath of any desired

part, a bar, m', is placed transversely beneath the collar M, within a suitable opening in the chuck L, and with its center is engaged one 70 end of a rod, m'', which from thence extends downward to and is connected with a block, m', that is placed within the spindle D, and through which passes the pin k. As thus arranged, an upward movement of the rod K 75 not only releases the clutch I from engagement with the pinion H, so as to arrest the rotation of the spindle D, but also raises the clutch-clamp l' and permits of the removal or insertion of work.

It is required that at one point in the rotation of the journaled head C each spindle D should have a period of rest for the purpose of enabling finished work to be removed and incomplete work substituted. Such point is 85 preferably the front of the machine, where there is secured to the housing B a bar, N, that extends downward and then horizontally inward, as shown. The rear portion of the horizontal section of said bar has its upper face, n, formed 90 upon an upward and forward inclination, and has such vertical position that as each of said spindles nears the front of said machine the lower end of its push-rod K will engage with said inclined face, n, and moving upon the 95 same will be raised, so as to release the clutch I and raise the chuck-clamp l'. Upon a further rotation of said head said rod will pass out of engagement with said tripping-lug and said clamp will be automatically drawn downward again and said clutch will resume engagement with its pinion.

The head C is given a step-by-step rotation by means of a ring, O, which is journaled upon its lower portion, and is provided with a spring-actuated pawl, o, that is adapted to engage with either of a series of notches, c', which are formed within a flange, c'', that projects outward from the lower end of said head. An arm, o', which extends radially outward from one side of said ring, enables the same to be rotated rearward upon and around its bearing, while by moving said ring forward said head is carried in the same direction. The head C is locked in position by means of a pawl, P, 115 which is pivoted upon the housing B in such position as to enable its free end p to engage with either of the notches c' as the same are brought into line with it. Said pawl is released from engagement by means of a lug, p', upon its side, which lug is engaged by a peripheral incline, o', upon the ring O, that occupies such relative position as to pass behind said lug p' and swing said pawl P outward just before said ring reaches the rear limit of its 125 motion, and its pawl o engages with one of the notches c', while as said ring moves forward said locking-pawl is released and left free for engagement with the next notch c' of the series. The number of said locking-notches corresponds to the number of spindles within the journaled head, and they are relatively arranged, so that each partial rotation of the latter brings one of said spindles to the front 130

center into position for the action of the chuck and clutch-releasing incline.

Upon the front side at the upper end of the frame A are two A-shaped vertical ways, a, 5 upon which is fitted a slide, Q, which has in plan view the general shape of a triangle, and at each of its angles is provided with a vertical opening, q, that is adapted to receive and contain a spindle, R, each of which spindles is 10 made vertically adjustable, and at its lower end is adapted to receive and contain a suitable tool-holder, r. The slide Q is reciprocated vertically by means of a lever, which is pivoted centrally within the frame A, and has 15 its front end in pivotal connection with said slide and its rear end in engagement with a circumferential groove, s, that is formed within the periphery of a horizontally-revolving cam, S. Said cam is secured to and rotates with a 20 shaft, T, which is journaled vertically within said frame and is moved by means of a horizontally-journaled shaft, U, that upon one end is provided with a belt-pulley, u, and upon its opposite end has a worm, u', which meshes 25 with a worm-wheel, t, upon said shaft T. Said cam is so timed as to move said slide slowly downward to the limit of its motion in such direction to allow a brief period of rest at such point, and then to raise said slide to the upper limit of its motion, where it is given a 30 longer period of rest.

The mechanism shown is adapted for use in pointing, drilling, and reaming or counterboring holes, for which purpose the left-hand spindle carries within its holder a pointing tool, V, the rear center spindle carries a drill, W, and the right-hand spindle carries a reamer or counterbore, X. Each spindle becomes idle when it reaches the front of the machine, 40 and while in such position is adapted to receive and discharge work.

In the use of the machine a piece of work, Y, which, for the purpose of illustration, is the setting-lever of a watch, is placed in position 45 upon the chuck of the idle-spindle and the journaled head then moved one-fourth of a revolution, by which movement said piece is clamped firmly in place and caused to revolve beneath the pointing-tool. The sliding head 50 now descends and said pointing-tool is brought into contact with said piece Y, within which it forms the desired conical recess. The tool-slide now rises, and the spindle-head is given another partial rotation, so as to bring the 55 part Y into position beneath the drill, when said slide again descends and said drill enters the point-recess previously formed and cuts within said piece of work a hole that has the predetermined size and depth, after which said 60 slide returns to its upper position again. The spindle-head is now given another partial revolution, so as to bring the part Y beneath the reamer or counterbore, which tool, upon the downward movement of the slide, completes 65 the opening within said piece of work, and is then raised, when, by a farther rotation of said spindle-head, the spindle, whose course

has been thus followed, is brought again to the front, where its rotation ceases, its chuck is opened, and the completed piece of work may 70 be removed and replaced by a new piece. All of the operations described are simultaneously carried on, so that at each partial rotation of said spindle-head a completed piece of work is removed and operations commenced upon 75 a new piece.

Having thus described my invention, what I claim is—

1. An organization in which is combined a series of rotatable work-holding chucks that 80 are adapted to have a step-by-step rotation around a common center, a series of tool-spindles that are less in number than said chucks and are each adapted to carry one of a series of pointing, drilling, and reaming or counter- 85 boring tools, means whereby each of said chucks may be moved into line with each of said tools and caused to rotate, and means whereby said tools may be simultaneously moved toward or from said chucks, whereby 90 all of the various operations of pointing, drilling, and reaming or counterboring may be simultaneously carried on upon an equal number of pieces of work, substantially as and for the purpose specified. 95

2. An organization in which is combined a series of tools that are adapted by successive action to point, drill, and ream or counterbore a series of rotatable work-holding chucks that exceed said tools in number and are each 100 adapted to be moved by successive steps into line with each of the latter, means whereby said tools may be simultaneously moved toward and from said chucks, and means whereby each of said chucks, after having passed 105 within the line of action of each tool of the series, has a period of rest, whereby each of the said operations of pointing, drilling, and reaming or counterboring may be carried on simultaneously with the insertion of new and 110 the removal of completed work, substantially as and for the purpose shown.

3. An organization in which a series of chuck-spindles are journaled at equidistant points within a pivoted head that is adapted 115 to have a step-by-step rotation around or upon its pivotal bearing, in combination with means, substantially as shown, whereby as each spindle is moved with said head one step from a predetermined point it is caused to revolve 120 within its bearings, and its revolutions are caused to cease when by the farther partial rotation of said head said spindle again reaches its starting-point, substantially as and for the purpose set forth. 125

4. An organization in which a series of chuck-holding spindles are journaled at equidistant points within a pivoted head that is adapted to have a step-by-step rotation around or upon its pivotal bearing, in combination 130 with means, substantially as set forth, whereby as each spindle is moved from a predetermined point by the partial rotation of said head its chuck is automatically closed and the

spindle caused to revolve within its bearings, and when by the complete rotation of said head said spindle reaches its starting-point it is automatically disconnected from its rotating mechanism and its chuck simultaneously opened, substantially as and for the purpose shown and described.

In testimony that I claim the foregoing I have hereunto set my hand this 14th day of May, 1886.

FRANK LEMAN.
